United States Patent Office.

W. S. POULSON AND W. N. POULSON, OF CADIZ, OHIO.

Letters Patent No. 97,960, dated December 14, 1869.

IMPROVEMENT IN TEACHERS' REGISTER.

The Schedule referred to in these Letters Patent and making part of the same.

To all whom it may concern:

Be it known that we, W. S. POULSON and W. N. POULSON, of Cadiz, in the county of Harrison, and State of Ohio, have invented a new and valuable Improvement in Teachers' Registers; and we do hereby declare that the following is a full, clear, and exact description of the construction and operation of the same, reference being had to the annexed drawings, making a part of this specification, and to the letters and figures of reference marked thereon.

Figure 1 of the drawings is a front view of our invention.

Figure 2 is a vertical section through same.

Figure 3 is a representation of a tablet, detached.

Our invention relates to records or registers for teachers' use, and consists, mainly, in the construction and novel arrangement of devices, whereby a record may be kept without the use of pen or pencil, and much waste of stationery may be avoided.

The letter A, of the drawings, designates a page of the register, in which are cut parallel perpendicular slots a a' , in the manner shown, the slot a being above the slot a' .

B represents a slip of tough paper, nicked at each end, in such a manner that when placed in the slots a a' , it will form a sliding tablet, the main portion of which is in rear of page, and the ends b b , by means of which the tablet is moved up and down, will appear in front.

The tablet is graduated, figures from 1 to 0 being printed or written thereon in regular order, commencing at the top with 1, and ending at the bottom with 0.

Horizontal slits are cut in the page between the slots a and a' , through which the tablets or slips are laced, so as to bring their full width to view between the slits, constituting the reading of the register. Generally, two tablets are used together, so as to form a combination of numbers from 0 to 99.

Immediately under the reading, and on the page, are printed or written such words as "absent," "late," "demerits," &c., and over the reading is laced, through the loops d d , a horizontal slip, C, on which is written the name of the pupil. This slip may be removed when it is so desired, and another substituted, bearing the name of a different scholar.

By the use of this register, much time will be saved to teachers, as there is no need of pen or pencil. Furthermore, the register is only dispensed with when worn out, as it will serve for many pupils.

What we claim as our invention, and desire to secure by Letters Patent, is—

The teachers' register herein described, having slots a a' , loops d d , and C, and sliding scale B, constructed and arranged to operate as specified.

In testimony that we claim the above, we have hereunto subscribed our names, in the presence of two witnesses.

W. S. POULSON.
W. N. POULSON.
